(57) CLAIM

The ornamental design for a medical dressing, as shown and described.

DESCRIPTION

FIG. 1 is a perspective view of a new design for a medical dressing;

FIG. 2 is a top view thereof;

FIG. 3 is a bottom view thereof;

FIG. 4 is a front view thereof;

FIG. 5 is a rear view thereof; and,

FIG. 6 is a right side view thereof, the left side being a mirror images thereof.

The surface shading illustrated in the drawings is provided merely to highlight the contour of design; it is not intended to be illustrative of texture or gloss and forms no part of the claimed design.
